(57) **CLAIM**

The ornamental design for a light, as shown and described.

DESCRIPTION

FIG. 1 is a top front perspective view of a light showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a front perspective view thereof showing a broken-line environmental table in use with the light.

The broken lines in the Figures show portions of the light and environment which form no part of the claimed design.

1 Claim, 6 Drawing Sheets
